UNITED STATES PATENT OFFICE.

OSBORNE I. PRICE, OF FREDERICK, MARYLAND.

DESIGN FOR A MEMORIAL TABLET.

54,125.

Specification for Design.

Patented Nov. 4, 1919.

Application filed March 7, 1919. Serial No. 281,315. Term of patent 3½ years.

To all whom it may concern:

Be it known that I, OSBORNE I. PRICE, a citizen of the United States, residing at Frederick, in the county of Frederick and State of Maryland, have invented a new, original, and ornamental Design for a Memorial Tablet, of which the following is a specification, reference being had to the accompanying drawing, forming part thereof.

The figure is a face view of a memorial tablet, showing my new design.

What is claimed is:

The ornamental design for a memorial tablet, as shown.

OSBORNE I. PRICE.

Witnesses:

WILLIAM BURRELL,
PAUL N. YESSLER.
